[57] CLAIM

The ornamental design for a mountain-shaped chocolate piece, as shown and described.

DESCRIPTION

The file of this patent contains at least one drawing executed in color. Copies of this patent with color drawing (s) will be provided by the Patent and Trademark Office upon request and payment of the necessary fee.

FIG. 1 is a top perspective view of the embodiment of our new design, comprising a two-colored mountain-shaped chocolate piece, where the piece is primarily red and has white cap top;

FIG. 2 is a front perspective view of the embodiment of FIG. 1, with the rear perspective view being a mirror image of the front perspective view;

FIG. 3 is a top perspective view of a second embodiment of our new design, comprising a mountain-shaped chocolate piece which is identical to FIG. 1 except that the colors are not specified; and,

FIG. 4 is a front perspective view of the embodiment of FIG. 3, with the rear perspective view being a mirror image of the front perspective view.

The bottom of the mountain-shaped chocolate piece forms no part of the claimed design.

Color drawings are necessary to show the color and contrast of the design claimed.
